CLAIM

The ornamental design for a hubcap, as shown and described.

DESCRIPTION

FIG. 1 is a front elevated perspective view of a hubcap showing our new design, the broken line showing of the tire and rim being for illustrative purposes only, and forms no part of the claimed design;

FIG. 2 is a front view of the hubcap design of FIG. 1;
FIG. 3 is a top view of the hubcap design of FIG. 1;
FIG. 4 is a bottom view of the hubcap design of FIG. 1;
FIG. 5 is a left side view of the hubcap design of FIG. 1; and,
FIG. 6 is a right side view of the hubcap design of FIG. 1.
